INVENTOR

UNITED STATES PATENT OFFICE

99,446

DESIGN FOR AN ALPHABET FOR FORMING MONOGRAMS

Sam H. Meister, New York, N. Y.

Application March 20, 1936, Serial No. 61,704

Term of patent 3½ years

To all whom it may concern:

Be it known that I, Sam H. Meister, a citizen of the United States of America, residing in Manhattan, county of New York, and State of New York, have invented a new, original, and ornamental Design for an Alphabet for Forming Monograms, of which the following is a specification, reference being had to the accompanying drawing, forming part thereof, wherein,

The figure is a plan view of an alphabet for forming monograms showing my new design.

The letters have no appreciable thickness.

I claim:

The ornamental design for an alphabet for forming monograms, substantially as shown and described.

SAM H. MEISTER.
